SHOE POLISHER MACHINE

William A. Beck, River Hills, Wis., assignor to Beck, Inc., Grafton, Wis.

Filed Nov. 2, 1970, Ser. No. 25,760

Term of patent 14 years

Int. Cl. D4—03

U.S. Cl. D4—37

FIG. 1 is a perspective view of a shoe polishing machine;

FIG. 2 is a side elevational view thereof;

FIG. 3 is an end elevational view thereof;

FIG. 4 is a plan view thereof; and

FIG. 5 is a bottom view thereof.

I claim:

The ornamental design for a shoe polisher machine, substantially as shown.
